UNITED STATES PATENT OFFICE

HARRY STEIGER, OF BALTIMORE, MARYLAND

DESIGN FOR A PLAYING UNIT FOR MARBLE GAMES

Application filed July 28, 1932. Serial No. 44,464. Term of patent 7 years.

To all whom it may concern:

Be it known that I, HARRY STEIGER, a citizen of the United States, residing at Baltimore, in the city of Baltimore and State of Maryland, have invented a new, original, and ornamental Design for a Playing Unit for Marble Games, of which the following is a specification, reference being had to the accompanying drawings, forming part thereof.

I claim:

The ornamental design for a playing unit for marble games, as shown.

HARRY STEIGER.
